(No Model.)

P. OSWALD.
HANDLE.

No. 521,217.

Patented June 12, 1894.

WITNESSES:

H. E. Chase,
S. Schoenbeck.

INVENTOR

A circular seal or stamp. At the top, the name 'Philip Oswald' is written in a cursive script. Below it, the word 'BY' is printed in a bold, sans-serif font. The bottom portion of the seal contains a signature that appears to read 'Hay Wilkinson & Parsons' followed by 'ATTORNEYS,' in a stylized, flowing script. The entire seal is set against a white background with a thin black border.

THE NATIONAL LITHOGRAPHING COMPANY
WASHINGTON, D. C.

UNITED STATES PATENT OFFICE.

PHILLIP OSWALD, OF SYRACUSE, NEW YORK, ASSIGNOR OF ONE-HALF TO
HELEN A. WELLS, OF SAME PLACE.

HANDLE.

SPECIFICATION forming part of Letters Patent No. 521,217, dated June 12, 1894.

Application filed August 22, 1892. Serial No. 443,713. (No model.)

To all whom it may concern:

Be it known that I, PHILLIP OSWALD, of Syracuse, in the county of Onondaga, in the State of New York, have invented new and useful Improvements in Handles, of which the following, taken in connection with the accompanying drawings, is a full, clear, and exact description.

My invention relates to improvements in handles particularly designed for satchels, grips, and similar devices, and has for its object the production of a neat, practical, and efficient device, which is extremely durable and is not liable to breakage when unduly strained or used continually; and to this end it consists in the detail construction and arrangement of the parts, all as hereinafter more particularly described and pointed out in the claim.

20 In describing this invention, reference is had to the accompanying drawings, forming a part of this specification, in which, like letters indicate corresponding parts in all the views.

25 Figure 1 is a side elevation of my improved handle shown as operatively secured to a portion of a supporting bar, the handle being illustrated as in its upright position. Fig. 2 is a similar view to Fig. 1, portions of the 30 parts being shown in section for further illustrating their detail construction and arrangement. Fig. 3 is an end elevation of the parts as shown at Fig. 1. Fig. 4 is a vertical sectional view of the handle, taken on line 35 —4—4—, Fig. 1, the hinge plate being shown as on the point of entering the aperture or eye of the ear formed at the extremity of the handle bar. Fig. 5 is a sectional view, taken on line —5—5—, Fig. 4, representing the 40 hinge bar in full lines in the position shown at Fig. 4 and in dotted lines as rocked from a horizontal position for facilitating its entrance to operative position, and Fig. 6 is an isometric perspective of the detached hinge 45 plate.

It is well known that the handles of satchels, grips, &c., are frequently broken, especially when subjected to great strain or when continually used.

50 My invention is of such peculiar construction and arrangement as to permit the same

to be subjected to great and unusual strain and to undue wear without liability of breakage, and is of such simple and practical construction that it is readily and economically 55 manufactured and assembled in operative position either upon satchels, grips, &c., in their manufacture, or upon those in use when desired to replace the old or broken handle with a new one.

60 —A— represents a supporting bar to which it is desired to secure my handle. This bar may be of any desirable construction suitable for the particular satchel or bag to which the handle is to be attached, and usually consists of a strip of sheet metal.

65 —B— represents the handle, consisting of a central portion or bar *a* rectangular in cross section and slightly thickened at its center to give greater strength, filling bars —*a'*—*a'*— 70 above and below the central portion or bar —*a*—, and a suitable casing —*a*²—. The central bar —*a*— is formed of suitable material as steel possessing the desired flexibility and strength, and is shown as formed at its ends 75 with integral enlarged ears —*A'*—*A'*— extending in substantially parallel planes.

70 The filling bars —*a'*—*a'*— are composed of leather or other suitable material, and the casing —*a*²— may also be composed of leather or 80 suitable material.

75 As clearly seen at Figs. 1 and 2 the filling bars —*a'*—*a'*— and the casing —*a*²— are sufficiently shorter than the central bar —*a*— to permit the ears —*A'*—*A'*— to project beyond their opposite extremities and the filling and casing rest against the shoulders formed at the upper ends of the ears —*A'*— to prevent slipping thereon. Each of the ears —*A'*—*A'*— is formed with a circular aperture or eye —*A*²— having on its lower side a pivotal bar —*A*³— and on its opposite side an upwardly extending rectangular slot —*A*⁴—.

85 —B'—*B'*— represent the hinge plates for 95 securing the handle —B— to the support —A—. These plates are of peculiar construction, and are preferably formed of brass or other firm, strong and rigid material. Each of the hinge plates is preferably composed of 100 a pair of feet —*b*—*b*— having their adjacent edges separated and of an ear or hinge bar —*A*⁴—.

—*b'*— having its opposite extremities secured to the adjacent edges of the feet —*b—b*— and its central portion raised above the top face of said feet —*b—b*— for forming a pivotal bar adapted to engage the corresponding pivotal bar of the handle bar ear. This bar —*b'*— is of less width than the feet —*b—b*—, and is formed rounding at the longitudinal edges of its under side for facilitating the swinging of the handle bar to one side or the other. This swinging of the handle is permitted by the peculiar construction of eye —*A²*— and hinge plate —*B'*—, since, as clearly shown at Fig. 2, the pivotal bar —*A³*— is of less thickness than the distance from the top face of the bar —*A*— to the under face of the pivotal bar —*b'*— of the hinge plates —*B'*—, and consequently said pivotal bar —*A³*— swings freely beneath the bar —*b'*— of the plate —*B'*— engaged thereby.

25 The hinge plates —*B'*— are firmly secured to the bar —*A*— by suitable clamps as bolts —*C*—. The handle bar is brought to the desired form and shape by a suitable cutting and bending device; the filling bars —*a'*— —*a'*— and the casing —*a²*— are then secured in position, and the hinge plates —*B'*— —*B'*— attached to the ears or extremities of the bar —*A*—.

30 At Figs. 4 and 5 I have shown the foot of one of the hinge plates as entering the eye —*A²*— and groove —*A⁴*—, of one of the ears of the handle bar, and it will be noted that the top edge of the central portion of the bar —*b'*— bears against the wall of the eye or aperture —*A²*—. By tipping the hinge plate into the position shown by dotted lines at Fig. 5 the lower right hand corner of the outer foot —*b*— passes to the outside of the bar —*A³*—, and, when the hinge plate is again brought to its horizontal position, the bar —*b'*— is operatively engaged with the bar —*A³*—.

35 The operation of my invention will be readily perceived from the foregoing description and upon reference to the drawings, and it will be particularly noted that, as the entire

central portion of the handle bar and its ears are formed of metal of considerable strength and as the hinge plates are also formed of metal, the wear of the hinged portion of these parts is very slight, and they are capable of supporting great weights without fracture, and that, owing to the simplicity of the device, it may be readily and cheaply manufactured, and may be attached in place of handles now used, or may be manufactured at the same time as the satchel or grip, and secured thereto to make a finished article.

Having thus fully described my invention, what I claim as new, and desired to secure by Letters Patent, is—

The herein described handle comprising a rigid central portion of rectangular cross section, thickened at its longitudinal center, and provided at each end with an enlarged integral ear forming a shoulder and having a circular eye with a rectangular slot at its upper side, filling bars on opposite sides of said central portion, and an outer casing surrounding the whole, said bars and casing resting at their ends against the shoulders of the ears; combined with two hinge plates each comprising two square feet arranged with their adjacent edges separated and each being of a size adapted to be turned on edge and passed through said eye and slot, and an upwardly bowed pivotal bar rounded on its under side and smaller than said feet to which its opposite extremities are integrally connected near the adjacent edges of the feet; a longitudinal supporting bar below the feet, and a bolt removably connecting each foot with this bar, all as and for the purpose set forth.

85 In testimony whereof I have hereunto signed my name, in the presence of two attesting witnesses, at Syracuse, in the county of Onondaga, in the State of New York, this 23d day of July, 1892.

PHILLIP OSWALD.

Witnesses:

CLARK H. NORTON,
M. BAXTER.
